Application September 29, 1934, Serial No. 746,194
In Austria August 25, 1934

14 Claims. (Cl. 92—61)

This invention relates to a process and apparatus for the manufacture from vegetable fibre pulp of sheets or slabs, particularly adapted for building purposes.

- 5 The advantage of the invention resides in the fact that slabs or sheets of every kind and size, e. g. hard slabs of dense quality resembling knotted wood, light slabs which are particularly suitable for insulating purposes, and porous slabs
10 which are especially adapted for sound-damping purposes, can be manufactured in the same apparatus. Owing to the fact that very extensive removal of liquid is effected in the first stages of the manufacturing process, the latter is also rendered
15 very economical, because high drying costs are spared. Further advantages of the invention will be apparent from the following description, which is explained with the aid of the accompanying drawings.
20 Referring to the drawings, Fig. 1 is an elevation partly in section of a press serving for pre-dehydration and pre-shaping,

Fig. 2 is a plan view of the same.

- Figs. 3, 4, and 5 are a side elevation, plan view
25 and a vertical section of a trolley carrier serving to transport the moulded sheets or slabs, and
Figs. 6 and 7 are elevations partly in section of the finishing press in the open and closed conditions respectively.

- 30 Figs. 8 and 9 are plan views of parts of the finishing press showing the differential grouping of the grooves for the removal of the water from the slab and the heating coils.

- The pre-dehydrating and pre-pressing device
35 1, briefly referred to as the pre-shaping box, consists of a frame 3 composed of four walls. Inside this frame a perforated base is provided which consists of two superimposed perforated plates or
40 perforated sheets 4 and 5. The plate 4 is fixed immovably in the frame, whilst the lower plate 5 is horizontally displaceable towards the left relatively to the upper plate, for which purpose a slot or groove 7 is provided in the frame wall. A toothed wheel 7a, which engages with a correspondingly toothed portion of the plate 5 and a hand lever 6 disposed outside of the frame 3 and connected by a shaft 7b with the toothed wheel 7a, serves to displace the plate 5. When the lever is rotated in the direction of the arrow s, the perforated plate 4 is displaced towards the left. The perforated base 4, 5 and accordingly the interior of the pre-shaping box, can be closed below by this displacement. A third perforated plate 10 is disposed loose on the perforated base. The arrangement is such that, when the central plate

is in the position not displaced towards the left, the perforations of the three plates all lie one above the other as shown in Fig. 1.

Below this perforated base 4, 5 a press ram device 8 is provided, on which a carrier frame 9 is disposed, which serves for the vertical displacement of the perforated base 4, 5. The interior of the carrier frame 9 is capable of attachment to a vacuum- and dehydrating lead 9a in order to enable the water to be sucked from the pulp introduced into the pre-shaping box 3 from the container 2. Above the pre-shaping box 3 a vertically displaceable press cover 11 is disposed, which on being lowered closes the box 3.

In Figs. 3 to 5 a trolley carrier, adapted to 15 transport the sheet or slab a pre-shaped in the pre-shaping box 3 and disposed on the plate 10, is illustrated. This trolley carrier consists of a frame, constructed from the angle iron 13, the sheets 13a and U-iron 12, for the displacement of which rollers 14 and handle 15 are provided.

The finishing press (Figs. 6 and 7) consists of a frame 16, onto which the plate 10 carrying the shaped sheet or slab is pushed with the aid of the trolley carrier. The frame box 16 is vertically 25 displaceable and is guided by the rods 17. The press ram 18 closes the under side of the frame box 16. This ram carries a table 19. A plate 21, provided with grooves or slots 21a, is disposed on the table with the aid of adjustable holding 30 down bolts 20. The final thickness of the slab or sheet can be regulated by adjustment of the holding down bolts 20. The plate is provided with a heating coil 22 which, owing to the fact that the coils are disposed closer together in the centre 35 than towards the edges, enable controlled heating to be effected insofar as the intensity of heat diminishes from the centre towards the edges. The heating coil is connected with a heat conduit 23, whilst the slots or grooves 21 are connected 40 with a vacuum lead 24. A press cover 25, which is provided with a press plate 26 constructed similarly to the plate 21, is disposed above the frame box 16 and is likewise connected to a heat conduit and a vacuum conduit. Both the lower and the 45 upper press plates are covered by perforated plates 27, in which the perforations are disposed closer together per unit surface in the central portion and wider apart per unit surface towards the periphery. Owing to the practically air-tight 50 closure of the pressing space formed by the frame 16 and the press ram a vacuum is formed on applying suction to which the plate is subjected for a longer time than in the known apparatus, so that as well as dehydration very extensive drying 55

takes place at a lower temperature than hitherto. With a view to removing moisture an alternative procedure on pressing, particularly when sizing materials known per se and adapted to unite the fibrous particles are added, is first to subject the sheet or slab of material to compression at a temperature, which is not sufficient to alter the condition of the binder contained in the material and to effect premature setting and hardening of the edges. Following this preliminary pressing and drying of the sheet or slab of material the latter is then pressed into the final desired shape and the binder softened and fixed under the application of high temperature.

15 The process of manufacturing the sheets or slabs is effected as follows:

After the lever 6 has been moved to the left and the base 4, 5 has been closed by displacing the perforated plate 5, the fibrous pulp is introduced with the aid of the rotatable feed pipe 2a from the container 2 into the mould or shaping box 3.

After the pulp has been introduced into the mould or pre-shaping box 3 the perforations in the base are so adjusted by displacing the lever 6 to the right that liquid can flow through the same. The press cover 11 is then lowered until it fits tight on the box 3. The press ram 8 is then raised, for which purpose a slot 9b is provided in the wall of the box for the introduction of the lead 9a; the liquid passes through the perforated base downwards into the interior of the carrier frame 9 and is removed by the water-discharge lead 9a which is with advantage connected with a vacuum. By the sudden opening of the base, aided by the suction action, a vortex effect is produced which causes a portion of the horizontally floating fibres to take up a sloping or vertical position. At the same time thickening takes place which stabilizes the lie of the fibres, this condition being fixed by compression. The principal effect of this procedure is to increase the strength of the sheets or slabs.

After a large portion of the liquid of the pulp has been removed in this manner and the same has been pre-shaped into the form of a sheet or slab a (Fig. 5) the cover 11 is raised. The trolley carrier 13 is then run over the shaping box 3 in such a way that it takes up a position 50 on the walls thereof. The two sheets 13a are then displaced to the left and right, respectively, in the direction of the arrow (see Fig. 5) until sufficient clearance is left for the upward passage of the perforated plate 10 carrying the cake or slab a. The press ram 8 is then raised to such a height that the perforated plate 10 and the cake or slab of material a thereon are pushed up into the trolley carrier, the lower edge of the plate 10 being disposed on a level with, or 55 a little above the top of the two sheets 13a, after which the latter are displaced to the right and the left, respectively, the edges of said sheets 13a passing between the plate 10 and the lower plates 4 and 5 then fixed down inside the trolley carrier and the latter is passed together with plate 10 and the pre-shaped slab disposed thereon out of the pre-shaping press.

The trolley carrier bearing the pre-shaped slab is then run on to the box 16 of the finishing press (Fig. 6). It is covered above by a perforated plate 28. The press ram 19 is then raised until the perforated plate 10 is disposed thereon and the trolley carrier 13 is then removed. The frame 16 is then raised so that it surrounds and closes 70 the press plate 21 and the moulded slab disposed

thereon on all sides. The press cover 25 is simultaneously lowered and covers the interior of the press box 16. On further raising the press ram 19 the pre-shaped slab is then finally compressed between the press plates 21 and 28 with simultaneous removal of the water by suction and heat, which causes evaporation of the liquid contained in the slab. As a result of the particular construction of the heating device described above and the use of perforations in the plate 27, controlled drying is accordingly simultaneously combined with the final pressing process, which ensures the sheets or slabs retaining their shape.

On completion of the final pressing process the ram 25 is raised. The box 16 is then lowered, 15 the trolley carrier run onto the same and the moulded slab pushed by the plunger 19 into the interior of the trolley carrier and there made fast. The trolley carrier together with the moulded slab is then pushed out and the latter 20 subjected to a finishing treatment.

The described method of dehydrating and heating the moulded slab in the final pressing treatment is of particular importance. In the described process of manufacture the four sides 25 of the moulded slab abut against the frame 16. Since the press plates 21 and 26 are heated, the frame 16 also becomes correspondingly heated. The moulded slab accordingly undergoes considerably stronger drying at the edges 30 than at the central portions, so that its moisture content is non-uniform. Owing to this non-uniform dehydration and drying, stresses are set up in the moulded slab, which during the final 35 drying process give rise to troublesome distortions. In certain circumstances the moulded slab shows this troublesome property of becoming distorted immediately on leaving the finishing press.

This invention accordingly makes use of a suitably controlled drying and dehydrating 40 process.

For this purpose the perforations in the perforated plates 27, which cover the pressing plates 21 and 26, are so constructed that the number 45 of perforations per unit surface diminishes or entirely vanishes towards the edges, so that greater opportunities are provided for the discharge of the water from the moulded slab in the centre than at the edges.

The heating device also is so adjusted that 50 more heat is given off at the centre of the plate than towards the edges.

The variation of the plate or slab for its different purposes as hard slab, porous slab, insulating slab or the like, is effected in the first place by 55 regulating the pressure exerted by the pressing ram, i. e. the properties of the material can be influenced and any desired kinds of plates, sheets or slabs be produced by regulating the degree of pressure exerted by the ram.

If the operation is effected substantially without pressure, soft porous plates or slabs are obtained. If medium pressure, such as 3 kgms., is employed, plates or slabs are obtained, which are admirably adapted for heat and sound insulating 65 purposes and which have an average specific gravity of 0.32.

If, on the other hand, the pressure is increased to 25 kgms. and more, and the pressing in the apparatus illustrated in Fig. 6 is combined with 70 drying at relatively low temperature, hard plates or slabs resembling knotted wood and having a specific gravity of about 1, are obtained as end products.

Hard plates or slabs are preferably subjected 75

to further subsequent drying and pressing treatment in a hydraulic press.

The quality of hard plates or slabs can be further improved by impregnating the plate or slab, 5 while being worked up in the hydraulic press, with 25 to 30% of water and again effecting compression in the hydraulic press at temperatures above 140° C.

What I claim is:

1. A device for the manufacture of plates, sheets or slabs of various properties from vegetable fibrous pulp comprising a finishing press adapted to receive the same from a preshaping mould and consisting of a vertically displaceable 15 mould-frame, pressing rams closing the same above and below during the treatment of the plate, the pressing rams carrying pressing plates and perforated plates, on top of the same the number of perforations per unit surface being 20 greater towards the centre.

2. A device for the manufacture of plates, sheets or slabs of various properties from vegetable fibrous pulp comprising a finishing press adapted to receive the same from a preshaping 25 mould and consisting of a vertically displaceable mould frame, pressing rams closing the same above and below during the treatment of the plate, the pressing rams carrying pressing plates, the latter being provided with a suction lead and 30 heating channels, which are more closely disposed towards the centre than at the edges.

3. In apparatus for the manufacture of sheets, plates and slabs from vegetable fibrous pulp in cooperative combination a preshaping mould 35 adapted to interlace the fibres of the pulp and a finishing press, the preshaping mould comprising a vertically movable frame, a closable base with three perforated plates, one of the same being horizontally displaceable relatively to the other 40 plates, the base being supported on pistons, a vertically movable cover, which closes the frame and a suction pipe connected to the space underneath the base.

4. In apparatus for the manufacture of sheets, 45 plates and slabs from vegetable fibrous pulp in cooperative combination a preshaping mould adapted to interlace the fibres of the pulp and preparing the slabs for a finishing press adapted to receive and finish the same, comprising a pair 50 of perforated base plates, means for moving one of said base plates to bring the perforations therein into or out of register with the perforations in the other plate, means for depositing pulp in said base plates, means for applying pressure to said pulp in a direction normal to the 55 surface of said base plates, means for applying suction beneath said base plates simultaneously with the application of pressure, and means for conveying the preshaped slab thus formed to 60 said finishing press having means for completing the manufacture of the slabs by applying pressure suction and heat.

5. In apparatus for the manufacture of large 65 sheets or slabs from vegetable fibrous pulp, in cooperative combination, a preshaping mould capable to interlace the fibres of the pulp and preparing the slabs for a finishing press adapted to receive and finish the same comprising a pair 70 of perforated base plates, means for moving one of said base plates to bring the perforations therein into or out of register with the perforations in the other plate, means for depositing pulp on said base plates means for applying pressure to said pulp in a direction normal to the 75 surface of said base plates, means for applying

suction beneath said base plates simultaneously with the application of pressure, and means for conveying the preshaped slab thus formed to said finishing press having means for completing the manufacture of the slabs by applying pressure suction and heat. 5

6. In apparatus for the manufacture of large sheets or slabs from vegetable fibrous pulp, in cooperative combination a preshaping mould capable of interlacing the fibres of the pulp and 10 preparing the slabs for a finishing press adapted to receive and finish the same comprising a closeable perforated base upon said mould, means for simultaneously applying pressure and suction to said pulp to preform it into a slab, means 15 for conveying said preformed slab to the finishing press, said finishing press being adapted to remove the water from the preshaped slab comprising a vertically displaceable mould-frame, 20 pressing rams closing the same above and below during the treatment of the plate, the pressing rams carrying pressing plates and perforated plates on top of the same, the number of perforations per unit surface being greater towards 25 the center.

7. In apparatus for the manufacture of large sheets or slabs from vegetable fibrous pulp, in cooperative combination a preshaping mould, a pair of perforated base plates upon said mould, means for moving one of said base plates to 30 bring the perforations therein into or out of register with the perforations in the other plate, means for depositing pulp on said base plates, means for applying suction beneath said base plates simultaneously with the application of 35 pressure, means for conveying the preshaped slab thus formed to said finishing press, said finishing press being adapted to remove the water from the preshaped slabs and press the same and comprising a vertically displaceable mould-frame, 40 pressing rams closing the same above and below during the treatment of the plate, the pressing rams carrying pressing plates and perforated plates on top of the same, the number of perforations per unit surface being greater towards the 45 center.

8. In apparatus for the manufacture of large sheets or slabs from vegetable fibrous pulp, in cooperative combination a preshaping mould capable of interlacing the fibres of the pulp and 50 preparing the slabs for a finishing press adapted to receive and finish the same, comprising a closeable perforated base, means for opening said base when the pulp is in position thereon, means for simultaneously applying pressure and 55 suction to said pulp to preform it into a slab, means for conveying said preformed slab to said finishing press, said finishing press being adapted to remove the water from the preshaped slabs and press the same, and comprising a vertically 60 displaceable mould-frame, pressing rams closing the same above and below during the treatment of the plate, the pressing rams carrying pressing plates and perforated plates on top of the same, the number of perforations per unit surface be- 65 ing greater towards the center, the said pressing plates being provided with a suction lead and heating channels which are more closely disposed towards the center than at the edges.

9. In an apparatus for the manufacture of 70 large sheets or slabs from vegetable fibrous pulp, a preshaping mould having means for simultaneously applying pressure and suction to said pulp to preform it into a slab, a closeable base consisting of three perforated, superposed plates, 75

- means to displace one of the plates to bring the perforations thereof in or out of register with the perforations of the other plates, the upper plate serving as a transporting means for the preformed slab to the finishing press, and means in said finishing press for applying at the same time pressure, suction and heat to complete the manufacture of the slab.
10. In an apparatus for the manufacture of large sheets or slabs from vegetable fibrous pulp, a preshaping mould having means for simultaneously applying pressure and suction to said pulp to preform it into a slab, a closeable base consisting of three perforated, superposed plates, means to displace one of the plates to bring the perforations thereof in or out of register with the perforations of the other plates, the upper plate serving as a transporting means for the preformed slab to the finishing press, and means in said finishing press for applying at the same time pressure, suction and heat to complete the manufacture of the slab, said finishing press comprising a vertically displaceable mould-frame, pressing rams closing the same above and below during the treatment of the plate, the pressing rams carrying pressing plates and perforated plates on top of the same, the number of perforations per unit surface being greater towards the center.
15. In an apparatus for the manufacture of large sheets or slabs from vegetable fibrous pulp, a preshaping mould including perforated base plates, means for moving one of said base plates, means for applying pressure to said pulp in a direction normal to the surface of said base plates, means for applying suction beneath said base plates simultaneously with the application of pressure, means for conveying preshaped slab thus formed to a finishing press, comprising a vertically displaceable mould-frame, pressing rams closing the same above and below during the treatment of the plate, the pressing rams carrying pressing plates and perforated plates on top of the same, the number of perforations per unit surface being greater towards the center.
20. In an apparatus for the manufacture of large sheets or slabs from vegetable fibrous pulp, a preshaping mould having means for simultaneously applying pressure and suction to said pulp to preform it into a slab, a closeable base consisting of three perforated, superposed plates, means to displace one of the plates to bring the perforations thereof in or out of register with the perforations of the other plates, the upper plate serving as a transporting means for the preformed slab to the finishing press, and means in said finishing press for applying at the same time pressure, suction and heat to complete the manufacture of the slab, said finishing press comprising a vertically displaceable mould-frame, pressing rams closing the same above and below during the treatment of the plate, the pressing rams carrying pressing plates and perforated plates on top of the same, the number of perforations per unit surface being greater towards the center.
25. In an apparatus for the manufacture of large sheets or slabs from vegetable fibrous pulp, a preshaping mould having means for simultaneously applying pressure and suction to said pulp to preform it into a slab, a closeable base consisting of three perforated, superposed plates, means to displace one of the plates to bring the perforations thereof in or out of register with the perforations of the other plates, the upper plate serving as a transporting means for the preformed slab to the finishing press, and means in said finishing press for applying at the same time pressure, suction and heat to complete the manufacture of the slab, said finishing press comprising a vertically displaceable mould-frame, pressing rams closing the same above and below during the treatment of the plate, the pressing rams carrying pressing plates and perforated plates on top of the same, the number of perforations per unit surface being greater towards the center.
30. 11. In an apparatus for the manufacture of large sheets or slabs from vegetable fibrous pulp, a preshaping mould including perforated base plates, means for moving one of said base plates, means for applying pressure to said pulp in a direction normal to the surface of said base plates, means for applying suction beneath said base plates simultaneously with the application of pressure, means for conveying preshaped slab thus formed to a finishing press, comprising a vertically displaceable mould-frame, pressing rams closing the same above and below during the treatment of the plate, the pressing rams carrying pressing plates and perforated plates on top of the same, the number of perforations per unit surface being greater towards the center.
35. 12. In an apparatus for the manufacture of large sheets or slabs from vegetable fibrous pulp, a preshaping mould having means for simultaneously applying pressure and suction to said pulp to preform it into a slab, a closeable base consisting of three perforated, superposed plates, means to displace one of the plates to bring the perforations thereof in or out of register with the perforations of the other plates, the upper plate serving as a transporting means for the preformed slab to the finishing press, and means in said finishing press for applying at the same time pressure, suction and heat to complete the manufacture of the slab.

neously applying pressure and suction to said pulp to preform it into a slab, a closeable base consisting of three perforated, superposed plates, means to displace one of the plates to bring the perforations thereof in or out of register with the perforations of the other plates, the upper plate serving as a transporting means for the preformed slab to the finishing press, and means in said finishing press for applying at the same time pressure, suction and heat to complete the manufacture of the slab, said finishing press comprising a vertically displaceable mould-frame, pressing rams closing the same above and below during the treatment of the plate, the pressing rams carrying pressing plates and perforated plates on top of the same, the number of perforations per unit surface being greater towards the center, the said pressing plates being provided with a suction lead and heating channels which are more closely disposed toward the center than at the edges.

13. In an apparatus for the manufacture of sheets, plates and slabs from vegetable fibrous pulp in cooperative combination a preshaping mould adapted to interlace the fibres of the pulp with a finishing press, the preshaping mould comprising a closeable base, means for closing the base during the introduction of the pulp into the mould, means for exerting a vacuum underneath the base and means for suddenly connecting the space above the base with the vacuum.

14. In an apparatus for the manufacture of sheets, plates and slabs from vegetable fibrous pulp in cooperative combination a preshaping mould adapted to interlace the fibres of the pulp with a finishing press, the preshaping mould comprising a closeable base, means for closing the base during the introduction of the pulp into the mould, means for exerting a vacuum underneath the base, means for suddenly connecting the space above the base with the vacuum, means for conveying the said preformed slab to finishing press and means in said finishing press for applying pressure, suction and heat to complete the manufacture of the slab.

HERMANN BASLER.
